TENNIS RACKET

Filed July 6, 1929

Inventor
Jacob L. Kleinman
By his Attorney
Edward S. Higgins

UNITED STATES PATENT OFFICE

JACOB L. KLEINMAN, OF NEW YORK, N. Y.

TENNIS RACKET

Application filed July 6, 1929. Serial No. 376,387.

This invention relates to tennis racket and more particularly to rackets of the adjustable type.

A primary object is to provide a racket with means for readily adjusting the tension of the strings.

Another object is to provide a racket with string adjusting means that take up a minimum of space in the playing field.

10 Still another object is to provide a racket that is simple in construction, durable in use and economical to manufacture.

Other objects and advantages of the present invention will appear from the description thereof to follow taken in connection with the accompanying drawing in which—

Figure 1 is a front view of a racket embodying my present invention.

Figure 2 is an enlarged sectional view 20 through the handle and part of the frame.

Figure 3 is an enlarged detail view of the movable bar.

Figure 4 is an enlarged detail view of the string supporting member, parts being 25 broken away for clearness.

Figure 5 is an enlarged detail view showing the connection between the movable bar and bushing member.

Figure 6 is a bottom plan view of the string 30 supporting member shown in Figure 4.

Figure 7 is a sectional view on the plane indicated by the line 7—7 of Figure 6.

Figure 8 is a detail view showing the 35 mounting of the string on the string supporting member.

Referring to the drawing in detail, my improved racket comprises a frame 10 supporting vertical strings 11 and horizontal strings 12 and a handle 13. The frame and handle

40 may of course be made of wood, metal or any other suitable material as desired. Formed in the inner periphery of the frame adjacent the handle is an elongated slot 14 and on either side of said slot are aligned openings 15 for a purpose which will appear.

The handle 13 is provided with an elongated chamber or recess 16 extending from the lower end thereof to a point a little beyond midway its length, which chamber terminates at its upper end in a bevelled roof

portion 17. Extending from this chamber through the handle to the slot 14 in the frame is a narrow bore 18. A bolt or pin 19 extends across the chamber 16 about midway its length. 55

A string supporting member 20, shown in Figure 4, is mounted in the slot 14. The depth of this supporting member is slightly greater than the depth of the slot 14 so that its upper edge, in which is formed a plurality of openings 21, extends above the inner periphery of the frame as will be noted from Figure 1. The body of this member is shaped to conform to the shape of the frame and is provided at its lower end with a narrow slot 60

22. Adjacent each side of the body portion is an elongated slot 23 which, when the supporting member is positioned in the slot 14, are adapted to register with the aligned openings 15 in the frame. The diameter of these 65 slots 23 are slightly greater than the diameter of the openings 15 so that pins or bolts passing through said openings and slots will secure the supporting member to the frame but at the same time permit up and down move-

ments of the supporting member as will be understood. The lowermost ends of all of the vertical strings 11 with the exception of the furthermost two on each side and the ends of the lowermost horizontal string 12 are 70 shown as passing through the openings 21 and are given a single twist as appears from Figure 8. After leaving the extreme end holes of the member 20, the string is looped twice through the frame, as indicated at 11', before it forms the extreme side runs which are not connected with the member 20, whereby loosening and slipping of the string is prevented. 75

Slidably mounted in the handle is a rigid member herein shown as a flat metal bar 24, terminating at one end in an eyelet or loop 25 and being turned over on itself at the other end to form an elongated loop portion 26. The elongated loop portion 26 is adapted 80 to move in the chamber 16 and encircles the pin 19. This pin guides the bar in its up and down movement and also prevents the turning of same. The remaining portion of the bar moves in the bore 18. The loop 25 is se-

80

85

100

cured to a pin or bolt 27 mounted in the member 20 and spanning the slot 22 as seen in Figure 4. On the lower end of the loop portion 26 is an externally screw threaded metal sleeve or bushing 28 connected to the bar by means of a pin 29.

Extending into the open end of the handle 13 and forming an extension thereof is an internally screw threaded sleeve 30 provided with an enlarged portion 31, and tapered shank 31' with a space therearound and secured thereto by means of a pin 32 is a ring member 33, said ring extending to a point slightly removed from the shoulder formed by the reduced and enlarged portions of the sleeve 30. On the upper edge of this ring 33 and between the ring and the edge of the handle is a washer 34. Resting on the other edge of the ring 33 and the outer edge of the sleeve 30 is a disc 35 and covering this disk and the outer edges of the ring 33 is a strip of leather 36, the edge of which is turned inwardly and disposed between the ring 33 and the outer gripping member 37 formed of leather. By reason of this construction, the extension of the handle is made very durable and a gripping means is provided which permits ready turning of the operating means.

In operation, the sleeve 30 is positioned over the bushing 28. When the sleeve 30 is turned to the right, the bushing 28, by reason of its screw threaded engagement with said sleeve, is moved downwardly carrying the bar 24 and associated parts along with it thereby tensioning the strings as will be understood. This movement is guided by the pin 19. Turning the sleeve 30 in the opposite direction of course releases the tension and permits the strings to become loosened.

40 The string supporting member 20, it will be noted, is provided with a plurality of peripheral slots 38 between the bearing members for the middle strings. This construction provides a minimum of resistance to the air in using the racket. On either sides of these slots 38 the supporting member 20 is uninterrupted by peripheral slots so as to strengthen and reinforce the racket at these points as there is considerable strain thereat when the strings are tensioned. This member 20 protrudes only a slight distance above the inner periphery of the frame affording very little obstruction to the playing field of the racket.

55 Supporting the strings on a member separate from the frame eliminates the necessity of boring holes in the racket at the neck portion as will be understood.

Although I have mentioned in describing my invention of what materials certain parts may be made, yet I desire it to be understood that this racket, or parts thereof, may be made of any suitable material and that various changes in details may be resorted to without departing from the spirit of the invention and

I desire to be limited only by the state of prior art.

I claim:

1. A tennis racket comprising a frame, strings within said frame, a handle, a rigid member, a string supporting member pivotally connected to said rigid member, and an extension forming part of said handle operatively connected to said rigid member for operating the same to tighten or loosen the strings. 75

2. A tennis racket comprising a frame, a handle, strings within said frame, a movable bar, a string supporting member pivotally connected to one end of said bar, the other end of said bar, provided with a screw-threaded portion and an extension forming part of said handle operatively connected to said screw-threaded portion for operating said bar to tighten or loosen the strings. 80

3. A tennis racket comprising a frame, a handle, strings within said frame, a movable bar, a string supporting member pivotally connected to one end of said bar, the other end of said bar, provided with a screw-threaded portion, a member adapted to engage said screw-threaded portion, said member having a portion forming an extension and a part of said handle. 85

4. A tennis racket comprising a string supporting frame, a handle, a device for tensioning the strings including a movable member and a pin carried by said handle for guiding the movement of said movable member. 90

5. A tennis racket comprising a frame, a handle, a movable string supporting member protruding from said frame, said protruding member formed with a slot, a pin in said slot and an element pivotally mounted on said pin and means for moving said element and said string supporting member. 100

6. A tennis racket comprising a frame, a hollow handle, strings supported by said frame, means for tensioning said strings including a rotatable extension forming part of the handle, said extension having a tapered portion extending inwardly of the main body of the handle the base of the tapered portion being of the same diameter as the inner wall of the main body of the handle to afford a bearing and the remainder of the tapered portion being spaced from the inner wall of the main body of the handle to minimize friction therebetween upon operation of said extension. 110

7. A racket comprising a frame, strings stretched within said frame, a handle, and a device for tensioning the strings comprising a string anchoring member, a rigid element movable longitudinally within said handle 125 and pivotally connected with said member and means whereby a pull may be exerted on said element to effect tightening of the strings.

8. A racket comprising a frame, a neck portion, a handle, strings within said frame, 130

a tensioning device for certain of said strings comprising a member engaging such strings, a rod within said handle, means for moving said rod longitudinally to tighten or loosen 5 said strings, and a pivotal connection between said member and said rod whereby said member may move angularly with respect to the latter.

9. A racket comprising a frame, strings 10 within said frame, a handle, a movable member protruding from said frame for supporting certain of said strings, said member pivotally connected to an element in a manner to permit relative movement therebetween, and 15 means for exerting a pull on said element.

10. A racket comprising a frame, a neck portion, a hollow handle, strings arranged in intersecting rows within said frame and defining the playing surface of said racket, 20 a string tightening device engaging certain of said strings, means for moving said tightening device longitudinally to tighten or loosen such strings, and means anchored in the racket structure below said playing surface 25 and engaging within said tightening device to resist rotational movement thereof.

11. A racket comprising a frame, a neck portion, a hollow handle, strings arranged in intersecting rows within said frame and 30 defining the playing surface of said racket, a string tightening device engaging certain of said strings, means for moving said tightening device longitudinally to tighten or loosen such strings, and means anchored in 35 the racket structure below said playing surface and passing through said tightening device to resist rotational movement thereof.

12. A racket comprising a frame, a hollow handle, strings supported by said frame, 40 means for tensioning said strings including a rotatable member, a portion of said member extending into the hollow of said handle and facing a portion of the inner wall of said handle, a part of each of said portions being 45 of the same diameter to afford a bearing, and the remaining part of at least one of said portions being tapered thereby minimizing friction therebetween upon operation of said member.

50 In testimony whereof I hereunto affix my signature.

JACOB L. KLEINMAN.
